UNITED STATES PATENT OFFICE

LEONARD D. NILSON, OF WAYZATA, MINNESOTA

PLANETARY OPERATING MECHANISM FOR LIFTING JACKS

Application filed October 27, 1927. Serial No. 229,117.

The object of my invention is to provide a lifting jack having a lifting arm pivoted at a high point of the frame of the jack but having the lifting end thereof adapted to be positioned relatively low when in lowered position and adapted to be relatively high when in raised position whereby it is especially adapted for use on automobiles having balloon tires.

10 A further object of my invention is to provide actuating means for the lifting arm in the form of planetary gearing mechanism whereby considerable leverage is obtained for raising the lifting arm.

15 Still a further object is to provide in a jack of this character a long low frame having lifting mechanism on one end thereof which can be conveniently wheeled into position beneath the axle of an automobile or the like when the tire thereon is "flat" for the purpose of raising such axle.

20 Another important object of my invention is to arrange the lifting arm to extend downwardly at an angle when in lowered position and to extend upwardly at an angle when in raised position, the lifting arm being pivoted for swinging movement from one of these positions to the other whereby the lifting arm when in intermediate position is substantially level.

25 From the foregoing object it will be obvious that more leverage will be had adjacent the lowered and raised positions of the lifting arm and less leverage at the intermediate position whereby more power is required at such intermediate position and it is therefore a further object of my invention to provide actuating means for the lifting arm which has a greater leverage at the intermediate position than it does adjacent the lowered and raised positions thereof for the purpose of counteracting the variation in leverage caused by the swinging of the lifting arm.

30 Still another object of my invention is to

provide a pair of curved rack bars on the frame of the jack and a pair of pinions journaled on the lifting arm and a ratchet wheel associated with the pinions whereby rotation may be imparted to the ratchet wheel for rotating the pinions, an operative connection being established between the pinions and the rack bars by intermediate pinions.

35 Still another object of my invention is to provide means for actuating the ratchet wheel, said means being pivoted at the rear end of the jack frame and adapted upon oscillation to cause movement of a lifting pawl which is associated with the ratchet wheel whereby rotation may be imparted to the mechanism for swinging the lifting arm.

40 Still a further object is to provide the oscillating means at the rear end of the jack frame in three parts, a notched sector, a lever and a handle, the lever being provided with a sliding dog to coact selectively with the notches of the sector.

45 Still a further object is to pivot the handle to the lever whereby the handle may be moved to a supine position resting on top of the jack frame so that the device, in effect, is folded for the purpose of transportation.

50 Still a further object is to provide a latching lever on the handle and a link connection with the dog or latch member, the connection of the link to the latch member coinciding with the pivotal connection of the handle to the lever whereby movement of the handle to a supine position does not affect or bend the latching mechanism.

55 Still a further object of my present invention is to provide a modified form of lifting jack having a gear and pinion operating connection between a pawl actuated ratchet wheel and a curved rack bar whereby the speed of the lifting arm relative to the speed of the ratchet wheel is considerably reduced which results in a jack especially adapted

to raise a comparatively heavy load such as a truck.

With these and other objects in view, my invention consists in the construction, arrangement and combination of the various parts of my planetary operating mechanism for lifting jacks whereby the objects contemplated are attained, as hereinafter more fully set forth, pointed out in my claims, 10 and illustrated in the accompanying drawings, in which:

Figure 1 is a side elevation of a jack provided with my improved planetary operating mechanism and showing the lifting head 15 in raised position and the operating handle in dotted lines assuming a supine position, as when the jack is folded for transportation.

Figure 2 is an enlarged plan view of the 20 rear end of the jack as viewed from the indicated line 2—2 of Figure 1.

Figure 3 is an enlarged detail sectional view of a locking mechanism for the operating handle of the jack and is taken on 25 the line 3—3 of Figure 1.

Figure 4 is an enlarged plan view of the front end of the jack showing the lifting head in lowered position parts being shown in section.

30 Figures 5, 6, and 7 are detail sectional views taken on the lines 5—5, 6—6 and 7—7 respectively of Figure 4.

Figures 8 and 9 are vertical detail sectional views taken on the lines 8—8 and 35 9—9 respectively of Figure 7.

Figure 10 is a sectional view of the ratchet operating mechanism of my jack illustrating the reversing mechanism for the lifting and locking pawls in operative position, 40 this figure illustrating the reversing mechanism operating to release the holding pawl from the ratchet wheel.

Figure 11 is a view similar to Figure 10 illustrating the reversing mechanism with 45 the lifting pawl moved to position where it is not affected by the reversing mechanism and is free to engage the ratchet wheel.

Figure 12 is a view similar to Figure 10 illustrating the lifting pawl rotating the 50 ratchet wheel whereby the locking pawl is free to be released from the ratchet wheel by the reversing mechanism.

Figure 13 is a view similar to Figure 10 illustrating the lifting pawl allowing the 55 load on the jack to rotate the ratchet wheel whereby the lifting pawl engages the reversing mechanism, removing it from contact with the locking pawl whereby the locking pawl is free to engage the ratchet wheel, 60 the pawls being illustrated in dotted line position as when the load is released from the lifting arm.

Figure 14 is a diagrammatical view of my jack illustrating the action of it whereby 65 the objects contemplated are attained.

Figure 15 is a vertical sectional view similar to Figure 5 and illustrating a modified form of operative connection whereby a greater speed reduction is had between the operating handle of the jack and the load 70 lifting head thereof; and

Figure 16 is a detail sectional view taken on the line 16—16 of Figure 15.

On the accompanying drawings I have used the reference numeral 10 to indicate the side frame members of my jack. The members 10 may be formed of channel bars or some suitable material and are made in pairs for forming a box-like frame construction. Secured to the forward end of each frame member 10 is a side frame casting 12, best illustrated in Figure 5 of the drawings. The castings 12 may be secured by bolts 14 to the side members 10 and by a bolt 16 spaced from the bolts 14. The bolts 14 each extend through one of the castings 12 and one of the members 10 while the bolt 16 extends through both members 10 and both castings 12. A spacing sleeve 18 is positioned on the bolt 16 between the castings 12 80 for holding the frame members 10 in proper spaced position with relation to each other and for forming a rigid frame work of the parts just described.

Another bolt 20 extends through ears 22 95 formed on the upper edges of the castings 12 in a manner similar to the bolt 16. A spacing sleeve 24 is provided on the bolt 20 and extends between the ears 22. The bolt 20 and the spacing sleeve 24 additionally 100 serve to impart rigidity to the jack frame.

The castings 12 are provided with bearings 26 through which a shaft 28 extends. The shaft 28 has journaled on its ends which extend beyond the bearings 26, a pair of 105 front wheels 30 for supporting the jack at its forward end.

A cross member 32 is secured to the rear end of the side frame members 10. The cross member 32 has formed thereon a pair of extensions 34 which may be bolted or riveted to the frame members 10. Each end of the cross member 32 is provided with a hub 36 adapted to rotatably receive a swivel caster 38. The casters 38 serve to support the rear 110 end of my jack.

It will be noted that the forward end of my jack is made relatively low whereby it may be conveniently rolled into position beneath the axle of the automobile when the tire thereon is deflated. A lifting head 40 is positioned at this low point of the jack frame as clearly illustrated in Figure 7.

For supporting the lifting head 40 and moving it to a raised position, I provide a lifting arm 42, best illustrated in Figure 6 of the drawings. The lifting arm 42 is pivoted on bolts 44 to a relatively high point on the side frame castings 12. The lifting arm 42 is really formed of two similar mem- 125 130

bers connected together by cross members 46 whereby a rigid lifting arm is formed pivotally supported at two points and by making it in one piece, danger of twisting is eliminated. The lifting arm 42 is pivoted to the lifting head 40 in the following described manner.

A lifting head socket 48 is provided with a pivot pin 50 which extends through it and then has each end riveted to a side of the lifting arm 42 as clearly illustrated in Figures 4 and 9 of the drawings. The lifting head socket 48 is provided with an opening 52 adapted to receive a shank 54 formed on the lifting head 40. The shank 54 is rotatably mounted within the opening 52 of the lifting head socket.

To prevent removal of the shank 54 from the socket an annular V groove 56 is provided around the shank 54. A pointed set screw 58 is screwed through a boss formed on the lifting head socket 48 so that it engages in the V groove 56. A lock nut 60 is provided on the set screw 58. The set screw 58 is adjusted so that rotation of the lifting head 40 may be had but the head cannot be removed from the socket 48. A rotatable lifting head 40 is desirable so that the jack may be swung from side to side while supporting a load.

It is desirable to at all times maintain the lifting head 40 horizontally and to accomplish this result I provide the following described mechanism.

Formed on the lifting head socket 48 is a pair of arms 62. The arms 62 are provided with bosses 64 through which extends a pin 66. Pivoted at one end by bolts 68 or the like to the castings 12 is a pair of stabilizing arms 70. The free ends of the arms 70 are riveted to the ends of the pin 66 which project from the bosses 64 formed on the lifting head socket 48.

The bolts 44 and 68, the pins 50 and 66, the lifting arms 42 and the stabilizing arms 70 form substantially a parallelogram for the purpose of maintaining the lifting head 40 in a substantially level position.

For actuating the lifting arm 42 for the purpose of swinging it on its pivot bolts 44 and thereby raising the lifting head 40 I provide a curved rack bar 72 formed on each side casting 12. In mesh with each rack 72 is what I term an intermediate pinion 74. The pinions 74 are journaled on pins 76 which are riveted to bosses 78 formed on the lifting arms 42.

In mesh with the intermediate pinions 74 are a pair of pinions 80 secured to a ratchet wheel shaft 82. The pinions 80 may be keyed or otherwise fixed relative to the shaft 82. The shaft 82 is journaled in bearings 84 formed on the lifting arms 42.

Secured to the central portion of the shaft 82 and positioned between the bearings 84

is a ratchet wheel 86. The ratchet wheel 86 is provided with a hub 88 adapted to extend between the sides of the ratchet wheel and the bearings 84. A lifting pawl link 90 is rotatably mounted on each hub 88 and extends upwardly between the bolts 44 on which the lifting arms 42 are pivoted.

The free ends of the links 90 are provided with a pivot pin 92 on which is pivotally mounted a lifting pawl 94. The free end of the lifting pawl 94 is adapted to engage the notches 96 of the ratchet wheel 86. The lifting pawl 94 is constrained to move into engagement therewith by a spring 98 coiled around the pin 92 and having parts 80 engaging the lifting pawl 94 and the links 90.

Pivoted on a pin 100 secured to the sides of the lifting arm 42 is a holding pawl 102. The holding pawl 102 is constrained to move into engagement with the notches 96 of the ratchet wheel 86 by a spring 104 coiled around the pin 100 and having parts engaging with the lifting pawl 102 and a portion of the lifting arm frame 42.

From the foregoing description it will be obvious that oscillation of the links 90 a sufficient distance will cause rotation of the ratchet wheel 86 in the direction of the arrow 106 and reverse movement of the ratchet wheel will be prevented by the holding pawl 102. Rotation of the ratchet wheel 86 will be transmitted through the shaft 82 to the pinions 80 and then through the intermediate pinions 74. This will cause the intermediate pinion 74 to travel on the racks 72 carrying with them the lifting arm 42 for the purpose of swinging and raising the load lifting head 40.

This movement will continue as long as the links 90 are oscillated the proper distance. To prevent the intermediate pinion 74 running off the forward ends of the rack bars 72 I provide stop lugs 108 formed on the lifting arms. The stop lugs 108 are adapted to engage the ends of the stabilizing arms 70 where they are pivoted on the bolts 68 to the side frame castings 12.

For causing oscillation of the links 90 I provide a handle 110 at the rear end of the jack frame. The manner of operatively connecting the handle 110 to the lifting mechanism at the front end of the jack will now be described in detail.

Pivoted on a bolt 112 at the rear end of the jack is a notched sector 114. The bolt 112 is supported by ears 116 extending from the feet 34 formed on the cross member 32. Pivoted on the bolt 112 and positioned on each side of the sector 114 is a lever 118. The levers 118 are connected together by a casting 120 and cap screws 122 and 124. The casting 120 slidably supports a latching member 126 adapted to coact with the

notches 128 formed in the sector 114. The latching member 126 is provided with a collar 130 and a spring 132 is interposed between this collar and a cross bar 134 of the casting 120 as clearly illustrated in Figure 2. The foregoing construction is for the purpose of constraining the latching member to engage the teeth 128. The latching member 126 is provided with a pair of ears 136 at its upper end.

A pair of handle bars 138 are pivoted to the bolts 122 on the outside of the levers 118. The downwardly extending ends of the handle bars 138 are provided with notches 140 adapted to swing into position with the cap screws 124 engaging the bottoms thereof. A yoke 142 best shown in Figure 3 is adapted to extend around the casting 120, the levers 118 and the handle bars 138, for the purpose of preventing undesired pivotal movement in one direction of the handle bars 138 with relation to the levers 118. Such movement in an opposite direction is prevented by the bottoms of the notches 140 engaging the cap screws 124.

The operating handle 110 is provided with an extension 144 adapted to be bolted between the upper ends of the handle bars 138 and to serve as a spacer therefor. A latch lever 146 is pivoted at 148 to the handle bars 138. The latch lever 146 has a link connection 150 extending from a pivot bolt 152 thereon to a pivot bolt 154 extending through the ears 136 of the latching member 126. A rod 156 extends through the latch lever 146 for being engaged by the hand of the operator when he desires to raise the latch member 126 from engagement with a notch 128 in the sector 114. The handle 110 can then be moved to any desired angle including a position adjacent the ground and the latch lever 146 can then be released to allow the latch member 126 to engage another one of the notches 128. In this manner the handle 110 is operatively connected to the sector 114 in any convenient position for proper operation of the jack.

The operating handle 110 is adapted to oscillate on the pivot bolt 112 and this oscillation is transmitted to the lifting pawl links 90 by the following described mechanism. A yoke member 158 is pivoted at 160 to the sector 114. The yoke member 158 extends rearwardly beneath the cross member 32 which at this point arches up over the yoke member. The rear end of the member 158 has formed thereon a screw threaded boss 162. A pair of stop extensions 164 is formed on the yoke member 158 back of the cross member 32. Another stop member 166 is formed on the boss 162 in front of the cross member 32. The stop members 164 limit the reciprocating movement of the yoke member 158 in one direction

and the stop member 166 limits such movement in an opposite direction. The purpose of this limitation of movement will herein-after be more fully described.

On the pivot pin 92 which extends through the lifting pawl links 90 I pivot a yoke member 168. The yoke member 168 has formed on its rear end a boss 170 which like the boss 162 on the yoke 158 is internally screw threaded. An operative connection is provided between the yoke members 158 and 168 by a connecting rod 172 having its ends screwed into the bosses 162 and 170. This construction allows for adjustment of the distance between the pivot pins 92 and 160 and such adjustment may be permanently retained by setting the lock nuts 174 against the bosses 162 and 170.

From the foregoing description it will be obvious that oscillating movement of the sector 114 will be transmitted through the connecting rod 172 to the links 90 whereby the lifting pawl 94 may be actuated to rotate the ratchet wheel 86 and thus impart lifting movement to the lifting head 40. The stops 164 and 166 are provided so that excessive oscillation of the lifting pawl is prevented. In other words, the distance between the stops is but slightly greater than the distance required to move the engaging end of the lifting pawl 94 from one notch 96 of the ratchet wheel 86 to the next one.

For imparting rotation to the ratchet wheel 86 in a direction opposite to the arrow 106 whereby the lifting head 40 may be lowered, I provide the following described reversing mechanism. A pivot pin 176 is mounted between the sides of the lifting arm 42. Journalized on the pin 176 is a pawl engaging lever 178. The pawl engaging lever is formed on a hub 180 which extends between bosses 182 formed on the lifting arm 42 for the purpose of receiving the pivot pin 176. A pair of arms 184 are formed on the hub 180 and a pair of springs 186 connect these arms to one of the cross members 46 whereby the pawl engaging lever 178 is constrained to move in the direction indicated by the arrow 188.

For preventing the movement just indicated I provide a pair of cables 190 connected at one end to the arms 184 and extending over pulleys 192 journalized on the lifting arm pivot bolts 44. The cables 190 then extend beneath the spacing sleeves 24 and toward the rear of the jack where they are connected to a reversing foot pedal 194. The pedal 194 is formed on one of a pair of arms 196 which have their forward ends pivotally mounted on the pivot bolt 112 at the rear end of the jack. A pair of curved links 198 are pivoted at 200 to the arms 196 and extend forwardly and over the pivot bolt 112 as clearly illustrated in Figure 1 of the drawings. A cross member 199

202 is provided for the arms 196 to cause their swinging movement to be coincidental. The cables 190 are fastened to the forward ends of the curved links 198. In Figure 1 5 it will be noted that the connections of the cables to the links 198 and the pivot connection 200 are on a line below the pivot bolt 112 whereby the pull exerted on the cables 190 serve to maintain the reversing foot 10 pedal 194 in the position illustrated in full lines due to a line between the connection of the cable to the link and the pivot connection 200 passing across the center of the pivot bolt 112. When the operator engages 15 the under side of the pedal 194 with his toe and lifts it, the levers 196 will move the links 198 to the dotted line position due to the pull of the springs 186.

When the pedal 194 is raised and the 20 cables 190 consequently slackened the pawl engaging lever 178 will move as indicated by the arrow 188 to the position illustrated in Figure 10. In this position the outer end of the lever 178 engages an extension 204 25 formed on the lifting pawl 94 and a boss 206 on the lever engages an extension 208 formed on the holding pawl 102. The operation of the reversing mechanism just described will hereinafter be more fully described.

In Figures 15 and 16 of my drawings, I 30 have illustrated a modified form of jack provided with gearing, which I will now describe in detail, for the purpose of a heavy 35 duty jack. In these two figures, parts corresponding to similar parts of the jack illustrated in the figures thus far described have been given the same reference numerals with the addition of the character "a."

In this type of jack, the ratchet wheel shaft 82a is journalled in the bearing portions 84a of the lifting arm members 42a. The pinions 80a may comprise teeth milled into an enlarged central portion of the shaft 45 82a and the ratchet wheel 86a is keyed or otherwise suitably secured to the shaft 82a. The pinions 74a which mesh with the curved rack bar 72a are journalled on the pins 76a, but instead of meshing directly 50 with the pinions 80a, they are provided with gears 75 which mesh with the pinions 80a. This gives a speed reduction in my jack making it suitable for use in raising the 55 wheels of heavy trucks. For supporting the pinions 74a and gears 75, each of the pins 76a is positioned with one end in the lifting arm 42a and the other end in an ear 43a constituting the end of a yoke 43 which is formed on the lifting arm as clearly 60 shown and extends around the pinion 74a and the gear 75. The ear 43a is shown in dotted lines in Figure 15, the ear being actually nearer the observer than the section 65 line upon which Figure 15 is cut. This

construction provides a substantial support for the pinion and gear.

Practical operation

In the practical operation of my improved lifting jack, the lifting head 40 is normally lowered to the position illustrated in Figure 7. This position is comparatively low and the forward end of the jack can therefore be wheeled into position beneath the axle of an automobile wheel or the like for the lifting of such axle. The operating handle 110 can be moved to the most convenient position relative to the sector 114 for operation by the user of the jack. It may here be mentioned that the jack can be placed under one of the axles of an automobile with the handle 110 extending from beneath the running board in which case the handle 110 would necessarily need to be adjusted to a low position in order to have room for proper operation. The sector 114 may then be oscillated for raising the lifting head 40. If desired the latching lever 146 can be moved in the direction of the arrow 210 for rendering the lever 110 in operative relative to the sector 114. A foot engaging pedal 212 on the sector 114 can then be operated by the toe of the operator for quickly raising the head 40 up to the axle of the automobile. After this normal operation of the jack may be had by releasing the latching lever 146. During the lifting movement of the lifting head 40 the ratchet wheel 86 is rotated in the direction of the arrow 106 by the lifting pawl 94 and reverse rotation thereof relative to the lifting arm 42 is prevented by the holding pawl 102.

It will be understood of course, that the pawl springs 98 and 104 actuate their respective pawls to engage the periphery of the ratchet wheel 86. As shown in Figure 7 the lever 178 is held in position so as to interfere with the action of the pawls and is held in such position by the cables 190 and foot pedal 194, the pedal and links 198 assuming the full line position illustrated in Figure 1.

When it is desired to utilize the pawl reversing mechanism for the purpose of lowering the lifting head 40 it is merely necessary to raise up on the reversing pedal 194 for allowing the springs 186 to act on the reversing lever 178. The springs 186 are designed stronger than the combined strength of the pawl springs 98 and 104 so as to render them inoperative. The pawl action during the lowering movement of the lifting head 40 is illustrated in Figures 10 to 13 inclusive of the drawings.

Assuming that the pawls are in the position illustrated in Figure 7 of the drawings the reversing lever 178 upon being released by upward movement of the reversing pedal 194 will move to the position illustrated in

Figure 10. In the position just referred to the lever 178 engages the extension 204 of the lifting pawl 94 and disengages it from the ratchet wheel 86. The holding pawl 102 is now holding the load on the lifting head 40 by reason of its engagement with one of the notches 96 of the ratchet wheel 86. The lifting pawl levers 90 are now moved in the direction of the arrow 214 as indicated 5 in Figure 11 which allows the extension 206 on the lever 178 to engage the extension 208 on the holding pawl 102. The lifting pawl 94 is now free to engage the next succeeding notch of the ratchet wheel 86 as illustrated 10 in Figure 12 of the drawings and the ratchet wheel will be moved a slight distance in the direction of the arrow 216 as movement of the lifting pawl is continued. This slight movement will release the load from the 15 holding pawl 102 so that the lever 178 causes it to disengage the ratchet wheel 86. The lifting pawl links 90 may then be moved in an opposite direction as indicated by the arrow 218 which allows the load on the load 20 lifting head 40 to carry the ratchet wheel 86 in the same direction as illustrated in Figure 13. As this movement continues, the next succeeding notch of the ratchet wheel 86 will engage the holding pawl 102 25 and the cycle of operations just described will be repeated as the lifting pawl links 90 are oscillated by the operating handle 110.

As soon as the lifting head 40 is lowered 30 to a position where it no longer engages the axle of the automobile due to the axle now being supported on the wheels thereon, the load will be removed from the ratchet wheel 86. In this event when the parts assume the 35 position illustrated in Figure 13, the tension of the springs 186 acting through the lever 178 is great enough to overcome the force of the pawl springs 98 and 104 and thereby move the lifting pawl 94 and the holding 40 pawl 102 to the dotted line positions illustrated. Thereupon the ratchet wheel 86 is free to rotate and the weight of the lifting arm and lifting head will cause the lifting head to be lowered to its lowest position 45 without further operation of the handle 110.

Diagrammatical illustration of the action of my planetary gearing

In Figure 14 of the drawings I have illustrated 50 the elements of my jack in diagram. The reference characters on this figure indicate the same parts shown in the other views of the drawings. The full line position of the lifting arm 42 and all of its associated parts indicate the lowered position 55 of the lifting head 40. The dotted line position illustrates the same parts when the lifting head 40 is in raised position.

The pivot pin 92 of the lifting pawl links 60 65 90 moves during its oscillation from the

position indicated to the center of the pivot bolt 44 as indicated by the line 220. It will be noted that this line is on an angle substantially the same as the angle of the lifting arm 42. The pull of the rod 172 is substantially horizontal so that it pulls at an angle on the pivot pin 92 which considerably increases the leverage obtained in the lifting pawl 94. However, it will be noted that the lifting arm 42 is also at an angle and therefore does not require quite as much force for raising it as when it is moved to the horizontal position indicated at 222. When in the position 222 the travel of the pivot pin 92 is substantially parallel to the 70 pull of the rod 172 as indicated by the line 224 whereby substantially the same amount of force is required on the rod 172 regardless of the position of the lifting arm. 75

When the lifting arm is raised to the 80 dotted line position the travel of the pin 92 will again be at an angle as indicated by the line 226 so that the force required for raising the lifting head is still the same. This construction provides an evenness of 85 operation of the jack without complicating its construction in any manner.

It is desirable to have the rack bars 72 a considerable distance from the pivot bolts 44 of the lifting arms 42 which would necessitate the ratchet wheel 86 being too close to the ground if the pinions 80 were in mesh with the rack bars. I have therefore provided intermediate pinions 74 so that the ratchet wheel 86 may be of substantial diameter and the rack bars 72 may be comparatively low and yet the parts are properly associated together through the medium of the intermediate pinions 74 for the purpose 90 of actuating the lifting arm. 95

From the description it will be obvious 100 that the handle 138 may be conveniently lowered to the dotted line position illustrated in Figure 1 for the purpose of compactly folding the jack so that it can be 105 crated for shipping without disassembling any of the parts.

Some changes may be made in the construction and arrangement of the various parts 110 of my invention without departing from the real spirit and purpose of my invention and it is my intention to cover by my claims, any modified forms of structure or use of mechanical equivalents, which may be reasonably included within their scope. 115

I claim as my invention:

1. A lifting jack comprising a frame, a downwardly curved rack bar thereon, having its ends in a substantially horizontal plane, a lifting arm pivoted to said frame, a ratchet wheel and a pinion journaled on said lifting arm, means for actuating said ratchet wheel for rotating said pinion and an intermediate pinion associated with said first pinion and with said curved rack bar 120 125

for causing pivotal movement of said lifting arm upon such actuation.

2. A lifting jack comprising a wheel mounted frame, a downwardly curved rack bar thereon having ends in a plane substantially horizontal mechanism mounted on one end of said frame, said mechanism comprising a lifting arm pivoted to said frame, a ratchet wheel and a pinion journaled on said lifting arm, means for actuating said ratchet wheel for rotating said pinion and an intermediate pinion associated with said first pinion and with said curved rack bar for causing pivotal movement of said lifting arm upon such actuation.

3. A lifting jack comprising a frame, a curved rack bar thereon having ends arranged in a substantially horizontal plane and close to the bottom of said frame, a lifting arm pivoted to said frame, a ratchet wheel and a pinion journaled on said lifting arm, means for actuating said ratchet wheel for rotating said pinion said pinion being spaced from said rack bar and an intermediate pinion associated with said first pinion and with said curved rack bar for causing pivotal movement of said lifting arm upon such actuation, said intermediate pinion comprising two parts, one part meshing with the curved rack bar and the other part meshing with said first mentioned pinion.

4. A lifting jack comprising the combination of a horizontal frame, a lifting arm pivoted thereto, a lifting head mounted on the free end thereof, a curved rack bar secured to said frame adjacent the bottom thereof, said rack bar having ends in a substantially horizontal plane rotatable means on said lifting arm, said means being operatively associated with said rack bar whereby rotation of the means imparts lifting movement to the lifting arm and means to rotate said rotatable means, step by step, in either direction.

5. A lifting jack comprising the combination of a horizontal frame, a lifting arm pivoted thereto, a lifting head pivoted to the free end thereof, means for maintaining said lifting head in vertical position throughout the pivotal movement of the lifting arm, a curved rack bar secured to said frame adjacent the bottom thereof, said rack bar having ends in a substantially horizontally plane rotatable means on said lifting arm, said means being operatively associated with said rack bar whereby rotation of the means imparts lifting movement to the lifting arm and means to rotate said rotatable means, step by step, in either direction.

6. In a lifting jack, a frame, a triangular lifting arm having pivotal connection at one of its corners with said frame, a lifting member carried by another of said corners, a curved rack bar on said frame, adjacent

the bottom thereof and having ends lying, in a substantially horizontal plane, means mounted on the remaining corner of said triangular lifting arm and operatively associated with said rack bar for causing the lifting head to be raised or lowered when said means is rotated and mechanism for imparting rotation in the desired direction to said means.

Des Moines, Iowa, September 30, 1927.
LEONARD D. NILSON.
